UNITED STATES PATENT OFFICE

163,864

COMBINATION CLOCK, THERMOMETER, AND BAROMETER

Michael Gold, New York, N. Y.

Application May 3, 1950, Serial No. 9,689

Term of patent 14 years

(Cl. D42—7)

To all whom it may concern:

Be it known that I, Michael Gold, a citizen of the United States of America, residing in the Borough of Manhattan, city of New York, county of New York, and State of New York, have invented a new, original, and ornamental Design for a Combination Clock, Thermometer, and Barometer, of which the following is a specification, reference being had to the accompanying drawing, forming part hereof.

Figure 1 is a top plan view of a combination clock, thermometer, and barometer, showing my new design.

Figure 2 is a front elevational view thereof.

Figure 3 is a side elevational view thereof.

I claim:

The ornamental design for a combination clock, thermometer, and barometer, as shown.

MICHAEL GOLD.
